UNITED STATES PATENT OFFICE

LOUIS W. COLE, OF NEW YORK, N. Y., ASSIGNOR TO COLE ELECTRIC PRODUCTS CO., INC.,
OF LONG ISLAND CITY, NEW YORK

LETTER BOX CONSTRUCTION

Application filed December 12, 1929. Serial No. 413,545.

This invention relates generally to letter boxes and has reference particularly to improvements in the construction of such boxes adapted for apartments housing a plurality of tenants.

To explain the general nature of my invention, I shall point out that in the manufacture of letter boxes embodying a plurality of compartments, it is desirable to utilize as many similar parts as possible, thus reducing the cost of production and installation.

It is, therefore, one object of my invention to provide a letter box made up of a plurality of upright receptacles, each thereof being exactly alike and having a lower door accessible to the tenant of the apartment, a frame marginally disposed about the receptacles and a single upper door for the entire bank of receptacles accessible to the post man.

A further object of the invention is to provide a receptacle for a letter box of the character described, which consists of a trough shaped length of metal having the free ends of the side walls offset and bent back upon themselves to form channels with adjacent walls into which the flanges of the lower door are received.

A still further object of the invention is to provide each separate receptacle with spaced projections or tabs at opposite ends, which tabs are inserted in openings or slots in a top and bottom wall and turned over on the latter to hold the parts together.

Another object of the invention is to provide a manifold frame which will fit marginally about a plurality of units and which will rest flush with the doors of the receptacles and surrounding wall in which the letter box is mounted.

I accomplish these objects by means of the various parts, combinations and arrangements thereof hereinafter described in the specification and set forth in the claims, the invention being illustratively exemplified in the accompanying drawings, in which Figure 1 is a perspective view of a letter box constructed according to my invention; Figure 2 is a transverse sectional view taken along the lines 2-2 of Figure 1; Figure 3

is a sectional view of one end of my improved mail box showing the various elements in perspective; Figure 4 is a sectional view illustrating the novel hinge means for mounting both upper and lower doors; Figure 5 is a sectional view of a portion of the bottom wall and means for anchoring the units to said wall; Figure 6 is a perspective view of a corner of the mail box showing the arrangement of the frame element; and Figure 7 is a perspective view of one of the receptacles or units.

Referring to the drawings, 10 denotes a receptacle of which any number may be juxtaposed side by side to form a bank corresponding to the number of apartments. Each unit comprises an integral sheet metal member having a back wall 11 and perpendicular side walls 12, the upper and lower ends of the latter having spaced tabs or projections 13, as illustrated in Figures 3 and 6. The front ends of the side walls 11 are offset slightly towards each other and then each is bent over on itself to form a bead 14, throughout the length of the unit, which bead when juxtaposed next to the adjoining unit forms one wall of a channel 15, as illustratively exemplified in Figure 2. It is to be noted particularly in connection with these units that each thereof is of the same dimensions, materials, etc. so as to make it practical to utilize any number of such units for a single installation.

About midway the height of each unit the bead 14 is cut away to form a slot 16 for the purpose of accommodating the lower edge of the upper door 17 or the upper edge of a lower door 18. According to the present invention each unit is provided with its own lower door 18, accessible to the occupant of an apartment, and consisting of a flat piece of sheet metal of dimensions corresponding to those of the lower half of the unit and having its longer sides bent perpendicularly to provide narrow flanges 19 adapted to occupy one half of the channels 15 when the door is closed over the front of the unit, as illustrated in Figure 2. A suitable lock 20 is provided for each door 18, the bolt of this lock being engaged in a slot 21 cut in the bottom wall 22.

Referring now to the bottom wall 22, the latter comprises a single strip of sheet metal of a length corresponding to the desired number of units, having an upright perpendicular back flange 23 against which the back walls 11 abut, and a perpendicular downwardly projecting front flange 24, which is flush with the ends of the beads 14. These elements of the invention are clearly illustrated in Figures 3 and 6 of the drawings. At spaced intervals throughout the bottom wall 22 are pairs of slots 25 into which the tabs 13 project prior to being bent over on the surface of the wall.

The top wall 26 is constructed of a strip of material exactly the same as that from which the bottom wall 23 is made, the back flange 27 in this instance projecting downwardly while the front flange 28 projects upwardly on the same plane as the flange 24. According to the construction thus far described, a plurality of units or receptacles 10 are banked side by side, the side walls 12 of the end units providing the upright sides of the assembly and the walls 22, and 26 forming the bottom and top walls, respectively, and serving to bind the structure together through the tabs 13 and slots 25.

The letter box consisting of the units 10 and top and bottom walls 26 and 22, respectively, is inserted into an opening left in the plaster or wall boards of the wall carrying the box and in order to finish off the box, I provide a frame 29 made up of strips of L-shaped metal having dimensions corresponding with the outside dimensions of the units, i. e., the longer flanges of the frame rest against the front face of the flanges 24 and 28, and the shorter flanges of the frame embrace the outer edges of the flanges 24 and 28, as illustratively exemplified in Figure 3. At the upright sides of the frame 29 the same are supported on the front flanges of L-shaped strips 30, the other flanges thereof being riveted or otherwise attached to the outside walls 12 of the end units.

Referring now to the upper door 17, the latter comprises a plate of dimensions corresponding to the overall dimensions of the plurality of units being utilized in the entire letter box, the upright sides of the plate are bent perpendicularly to form flanges 31, which engage in the spaces or grooves formed by the outside beads 14 of the end units and the attached flanges of the L-shaped strips 30. The upper ends of the beads 14 are cut away to accommodate a re-enforcing bar 32 which is attached by means of rivets 33 to the door 17 adjacent its upper end, as illustrated in Figure 3. The bar 32 also carries a single lock accessible through a key slot 34 at the front of the door.

The means by which the lower doors 18 and upper door 17 are hinged to the units is illustrated in detail in Figure 4. The

upper ends of the flanges 19 of each lower door 18 are hinged in the beads 14 adjacent the lower end of the slot or cut out 16 on pins 35. The hinged ends of the flanges 19 are inclined downwardly away from the front plate so as to enable the door 18 to swing to horizontal position before engaging the lower wall of the cut out 16. The upper door 17 is similarly hinged except that the lower ends of its flanges 31 are at right angles thereto and hinge on their respective pins 36. Intermediate the width of the upper door 17 the lower end accommodates hinge blocks 37 which project inwardly from the inner face of the plate and enter the grooves formed by adjacent beads 14 just above the cut outs 16. Each block 37 hinges on a pin 38 mounted in the beads 14 on opposite sides thereof.

It will suffice to state, in connection with the construction of the letter box described in detail in the foregoing paragraphs, that boxes of any number of units may be fabricated according to the present invention, by simply providing strips of material forming the upper and lower walls 22 and 26 of different dimensions to accommodate the different combinations, and frames 29 and upper doors 17 which will also mount the same combinations of units. Thus the manufacturer need only provide himself with a large number of units or receptacles and upper doors 17 of the various sizes required of different combinations of such units. The frames 29 will also have to be made in the same various sizes, but since both the doors 17 and frames 29 are of such simple construction the cost of manufacturing these parts is relatively small and the same may be easily stocked. The last items are the top and bottom walls but since they are just alike and may be manufactured in long strips from which the desired lengths may be cut, the stocking of this particular material does not add to the actual manufacturing cost, as would be the case if special castings or parts were required for both top and bottom members as well as for the various sizes of letter boxes.

Having now described my invention what I claim and desire to secure by Letters Patent is:

1. A letter box comprising a plurality of upright juxtaposed receptacles, each receptacle having side walls which are offset inwardly along their forward ends, said offset ends forming channels with adjacent offset ends of the next receptacles, a door hinged midway the height of each receptacle and having side flanges to engage in said channels in the closed position of the door and a single door hinged at the mid portion of the box and closing over the remainder of all the receptacles.

2. A letter box, comprising a plurality of upright juxtaposed receptacles, each thereof having the forward ends of its side walls

bent back upon themselves and offset inwardly with respect to the plane of the side walls, the mid portion of the offset ends being cut away, said offset ends forming a channel 5 with the corresponding offset end of the adjacent receptacle, a hinged door for closing the portion of each receptacle below the cut away portion and having side flanges to engage in said channels, the hinge for said door 10 being disposed just below the lower end of said cut away portion, and a single hinged door for all the upper portions of said receptacles and having side flanges to engage against the offset ends of the outside walls of 15 the end receptacles, the hinge for the upper door being disposed in the offset ends just above the cut away portion thereof.

3. A letter box, comprising a plurality of upright receptacles, each thereof being 20 formed of sheet metal having a back wall and forwardly extending side walls, the front ends of which are bent back upon themselves and then offset towards each other, the mid portion of the ends being cut 25 away and provided with openings adjacent the ends of the cut out portions, the opposite ends of the side walls being provided with projecting tabs, a door pivoted in the lowermost pair of openings in the forward ends 30 and having side flanges to engage in the offset portions of the forward ends.

4. A letter box, comprising a plurality of juxtaposed similar upright receptacles, an individual door for closing the lower portion 35 of each receptacle, a single door for closing the upper portions of all the receptacles, similar manifold top and bottom plates for the juxtaposed receptacles, said plates having oppositely projecting flanges, 40 one thereof engaging over the back of the receptacles and the other projecting upright and flush with the doors, similar angle pieces secured along one side of each to the outer sides of the end receptacles, the other sides 45 of the pieces being flush with the said front flanges of the top and bottom plates, and a flanged frame embracing the front and free edges of said flanges.

5. A letter box, as claimed in claim 4, in 50 which the upper and lower ends of the side walls of each receptacle are provided with projecting tabs which project through slots in the top and bottom plates and are turned over on the outside faces thereof to hold 55 the receptacles together, substantially as described.

6. A letter box, as claimed in claim 4, in 60 which the forward portions of the bottom plate midway between the side walls of each receptacle are provided with slots, and a lock carried at the free end of each lower door having its bolt engaging in a slot to lock the door in closed position.

7. A letter box, as claimed in claim 4, in 65 including a lock for each door, the bottom

plate having openings to accommodate the bolts of the locks on the lower doors and the top plate having a single opening to receive the bolt of the lock on the upper door.

8. A mail box, as claimed in claim 2, in 70 which hinged ends of the flanges of all the doors are inclined towards the free ends of the doors to permit the doors to swing open to horizontal position.

9. A mail box, as claimed in claim 2, in 75 which the upper ends of the offset front ends of the side walls of the receptacles are cut away, and a bar is carried transversely of the inner face of the upper door adjacent its free end to rest in the space left by the said cut 80 away portions.

In testimony whereof he has affixed his signature.

LOUIS W. COLE.
